DESIGN FOR A REFRACTING BOWL FOR LIGHTING FIXTURES

Thomas W. Rolph, Newark, Ohio, assignor to
Holophane Company, Inc., New York, N. Y., a
corporation of Delaware

Application June 26, 1940, Serial No. 93,250

Term of patent 14 years

To all whom it may concern:

Be it known that I, Thomas W. Rolph, a citizen of the United States of America, and a resident of Newark, in the county of Licking and State of Ohio, have invented a new, original, and ornamental Design for a Refracting Bowl for Lighting Fixtures, of which the following is a specification, reference being had to the accompanying drawing, forming a part thereof.

In the drawing:

Figure 1 is a side elevational view of a re-

fracting bowl for lighting fixtures, with parts in section, showing my new design;

Figure 2 is an inverted plan view with parts broken away; and

Figure 3 is a perspective view of the same at a reduced scale.

I claim:

The ornamental design for a refracting bowl for lighting fixtures, as shown.

THOMAS W. ROLPH.
